UNITED STATES PATENT OFFICE.

GEORGE M. SCHOTT, OF CINCINNATI, OHIO, ASSIGNOR TO CINCINNATI GALVANIZING COMPANY, OF CINCINNATI, OHIO, A CORPORATION OF OHIO.

CAN.

1,116,496.

Specification of Letters Patent. Patented Nov. 10, 1914.

Application filed November 25, 1911. Serial No. 662,259.

To all whom it may concern:

Be it known that I, GEORGE M. SCHOTT, a citizen of the United States of America, and resident of Cincinnati, county of Hamilton, 5 and State of Ohio, have invented certain new and useful Improvements in Cans, of which the following is a specification.

An object of this invention is to produce an improved can or metal receptacle; and 10 also an improved method or process of manufacturing the same. One of the difficulties ordinarily encountered in the manufacture of large metal cans or receptacles, is that the heat to which the cans are subjected during 15 the galvanizing operation sets up inherent and unequal temperature strains in the metal of the can, and often causes the can to distort to such an extent, that it is rendered useless. This difficulty is more likely to be 20 encountered in the manufacture of large rectangular cans employed in refrigerating apparatus as the receptacles for the water to be frozen, than in the manufacture of other cans, since a slight distortion of the metal 25 forming the body portion of the can, will destroy the can's usefulness by preventing the easy removal of the ice from the can.

One object of this invention is to produce a can particularly adapted to be used as a 30 receptacle for water to be frozen in the manufacture of ice, and also to produce an improved method of manufacturing the can, which will prevent the objectionable distortion above referred to. This, together with 35 other objects, I attain by means of a can embodying the features illustrated and described in this application, and by adhering to the method of manufacturing cans, which is herein set forth.

40 In the drawings accompanying and forming a part of this application, Figure 1 is a perspective view of a can embodying my invention, and formed in accordance with the novel process or method of manufacture 45 herein described. Fig. 2 is a fragmental plan view of the upper edge of the can shown in Fig. 1. Figs. 3 and 4 are fragmental sectional views of the can shown in Fig. 1, and respectively show the construction of the upper edge and at the bottom of the can.

The can illustrated as an embodiment of my invention consists of a body portion 5, formed of corrugated sheet metal, and a base 55 portion 6, which is preferably, but not neces-

sarily formed of sheet metal, and is provided with means, such as a flange 7, formed by bending the edge of the metal blank, of which the base is formed, for securing the base to the body portion. The bottom is 60 shewn secured to the body 5, by means of rivets 8, but it may be secured in place by any suitable means, and, if desired, may be corrugated, like the body portion of the can. The corrugations of the body portion extend 65 parallel to the vertical axis of the can, that is, from the closed bottom to the open top of the can. The corrugations may extend in any desired direction, so as to stiffen the can laterally or longitudinally, as desired, but in 70 cans adapted to be employed as receptacles for water to be frozen, the corrugations must extend from the top to the bottom of the can, so that the blocks of ice formed therein can be removed therefrom, without difficulty. In addition to this, the corrugations at the top and bottom of the can must be specially formed, so that there will be no re-entrant or inwardly projecting shoulders or 75 lugs, which will prevent the ice from slipping longitudinally out of the can. For these reasons, I have so formed the corrugations that a flat riveting edge 9 is formed at the top of the can, with its inner surface 80 flush with the bottom portions of the grooves, formed on the inside of the can by the corrugations, and a flat riveting edge 10 is formed at the bottom of the can, and is so located that its inner surface is flush with the innermost portions or apexes of the 85 ridges formed on the inside of the can by the corrugations. With this arrangement, the lower ends of the ridges on the ice formed in the can will taper off to a flat surface, and there will be no projecting shoulders on the block of ice, which will prevent it from being easily removed from the can. The riveting flange 7 of the bottom 6 of the can is shown located on the outside of the 90 riveting edge 10 of the body portion 5. This, however, is not necessary, since the flange 7 may be located on the inside of the body portion, without detrimentally affecting the utility of the can. The rivets 8 are necessarily counter-sunk at their inner ends, so that 95 they will not form projecting lugs, which will prevent the removal of the ice. I have provided a reinforcing band 12 at the top of the can, which is shown secured on the outside of the body portion, around the rivet. 100

105 110

ing edges 9, by means of rivets, which are counter-sunk at their inner ends. It will be understood that the reinforcing band 12 may be omitted, if desired, and that the corrugations may extend to the upper edge of the can, or that the riveting edges 9 may be so formed, that the reinforcing bands 12 may be located on the inside of the upper edge of the can, without obstructing the ends of the grooves formed by the corrugations.

The lateral edges of the sheet metal forming the body portion 5, are shown riveted together along a line parallel to the vertical axis of the can. Any convenient method may, however, be employed for securing these edges together, which does not produce projecting lugs or shoulders on the inside of the can.

Cans of the kind above described are ordinarily formed of sheet iron, and are made up after the sheets are galvanized. It is highly desirable to subject the can to the galvanizing process after its parts have been assembled and secured together, since the joints and the connections are all galvanized and the seams are filled with zinc or other galvanizing metal employed, and a more perfect can is produced than is the case when the metal forming the can was first galvanized and then manufactured into a can. The heat to which the can must necessarily be subjected during the galvanizing operation, is apt to, and often does, cause the metal of which the rectangular body portion is formed, to expand unequal amounts and to thereby distort the sides of the can to such an extent, that the can is

rendered useless for the purpose for which it was intended.

While I have described my invention as applied to receptacles or molds for making ice, I desire it to be understood that receptacles embodying my invention may be otherwise utilized and that various changes and modifications, substitutions and omissions may be made by the apparatus illustrated, without departing from the spirit and scope of my invention as set forth by the appended claims.

What I claim is:

1. An ice mold comprising a body portion having unobstructed longitudinally extending parallel grooves formed on the inside faces of the side portions thereof, and a bottom connecting edge formed on the side portions thereof with its inner surfaces located flush with the apexes of the ridges formed between said grooves, and a bottom secured to said edge.

2. An ice mold having a rectangular body portion with longitudinally extending corrugations formed therein, a bottom connecting flange formed along the lower edge thereof, flush with the apexes of the corrugations on the inside of the can and a lip flange formed along the upper edge thereof, flush with the apexes of the corrugations on the outside body portion and a bottom secured to said bottom connecting flange.

GEORGE M. SCHOTT.
